UNITED STATES PATENT OFFICE.

JOHN CENDER, OF FOOSLAND, ILLINOIS.

JACK.

Application filed August 2, 1923. Serial No. 655,276.

To all whom it may concern:

Be it known that JOHN CENDER, a citizen of the United States, residing at route 1, box 6, Foosland, in the county of Champaign and State of Illinois, has invented certain new and useful Improvements in Jacks, of which the following is a specification.

This invention relates to a lifting jack and has for its principal object to provide a simple and efficient means for use in connection with a corn sheller and acts as a prop for the main drive shaft to keep the belt from slipping thereby causing the corn sheller to at all times be in a proper operative position when in use.

Another important object of the invention is to provide a jack of the above mentioned character, which when in use upon a corn sheller will prevent jarring and will cause the corn sheller to operate more easily and which will not interfere with the operation of the same.

A further object of the invention is to provide a jack of the above mentioned character, which may also be used for any other suitable purpose and which will efficiently operate under all circumstances.

Another important object of the invention is to provide a jack of the above mentioned character which is simple in construction, inexpensive, strong and durable and very well adapted for the purposes for which it is designated.

Other objects and advantages of this invention will become apparent during the course of the following description.

In the accompanying drawings forming a part of the specification and in which like numerals designate like parts throughout the same.

Figure 1 is a vertical section of my invention.

Figure 2 is a section taken on line 2—2 of Figure 1; and

Figure 3 is a section taken on line 3—3 of Fig. 1.

In the drawings wherein for the purpose of illustration is shown the preferred embodiment of my invention, the numeral 1 designates the tubular stand which is provided at one end with the base or end plate 2. The opposite end of the tubular member 1 is provided with a vertically extending slot 3 which extends from the open end

of the standard inwardly for a suitable distance and the purpose of this slot will be hereinafter more fully described.

The tubular standard 1 is furthermore provided with a longitudinally extending slot 4 provided in the intermediate portion thereof and the purpose of this slot will be hereinafter more fully described.

Slidably mounted in the standard 1 is the elongated cylindrical member 5. The cylindrical member 5 is provided with a series of longitudinally extending teeth which form a rack bar 7 and this rack bar is adapted to be mounted on the cylindrical member 5 adjacent its upper end. The rack

bar 7 is furthermore adapted to co-operate with the vertically extending slot 3 provided in the upper end of the tubular standard 1 and the lower end of the cylindrical member 5 is provided with a pin 8 which extends through the longitudinally extending slot 4 for the purpose of preventing the rotary movement of the cylindrical member 5 within the tubular standard 1 when the same is in operation. Mounted

on the upper end of the tubular standard 1 is the bracket 9 and this bracket 9 comprises a flat strip of metal encircling the tubular standard 1 and having its free end extending beyond the side of the standard and adapted to receive the transversely extending pin 10. Pivotedly mounted on the transverse pin 10 and disposed between the free ends of the arms of the bracket 9 is the pawl 11.

The pawl 11 has its free end adapted to engage the ratchet teeth 6 provided on the rack bar 7 and for the purpose of normally holding the pawl in engagement with the ratchet teeth on the rack bar, I provide the flat spring 12. This flat spring 12 being secured at its lower end to the tubular standard and having its upper free end slidably associated with the intermediate portion of the pawl 11 in the manner as further shown in the drawings.

Fulcrumed on the transversely extending pin 10 is the lever 13. This lever 13 has its inner end forming a substantially U-shaped member which encloses the free end of the outwardly extending arms of the bracket 9 and through which is adapted to extend the transversely extending pin 10. Pivotedly mounted in the U-shaped portion of the lever 13 and preferably on the end 14 is the pawl 15. This pawl 15 is of a

100

105

110

longer length than the pawl 11 and the upper end of the pawl 15 is also adapted to engage the ratchet teeth 6 on the rack bar 7. This last mentioned pawl is designated 6 as an actuating or operating pawl for the purpose to be more fully described.

In order to insure the proper operation of the pawls 11 and 15 respectively, and to keep the same in engagement with the 10 ratchet teeth on the rack bar, I provide a guide member 16. This guide member 16 is mounted on the tubular standard 1 adjacent the outer free end thereof and extends outwardly therefrom and encloses the 15 intermediate portion of said pawl in the manner as clearly shown in the drawings.

The pawl 11 is adapted to act as a means for normally holding the upper free end of the cylindrical member 5 in its adjusted position 20 and when it is desired to raise the cylindrical member 5 to a higher height the lever 13 is actuated in such a manner as to cause the lifting of the cylindrical member, by the actuation of the pawl 15. When the lever 13 is swung downwardly the pawl 15 is pulled 25 out of engagement with the ratchet teeth on the rack bar 7, but the shorter pawl 11 will be in engagement with the ratchet teeth and hold the cylindrical member 5 in the adjusted 30 position. If it is desired to raise the cylindrical member 5, the lever 13 is swung upwardly and this causes the pawl 15 to again engage the ratchet teeth on the rack bar above the pawl 11 and consequently result in 35 the lifting of the cylindrical member 5 to its predetermined length or height. In this manner, it will be seen that there is no possibility of the cylindrical member becoming accidentally lowered for the reason that the 40 pawl 11 which acts as a stationary member will hold the cylindrical member in adjusted position.

When it is desired to release the pawl 11 from engagement with the rack bar so that 45 the cylindrical member 5 may be lowered, the pawls are disengaged from the ratchet teeth on the rack bar and the coil spring 17 which is connected at one end to the base 2 and at its 50 opposite end to the lower end of the cylindrical member 5, will cause the retraction of the cylindrical member 2 into the tubular standard 1 immediately upon release of the pawls from engagement with the rack bar mounted on the upper end of the cylindrical 55 member.

The purpose of providing the slots in the tubular standard 1 is to prevent the rotation of the cylindrical member 5 when the same is being actuated by the pawls 11 and 15 60 and will thereby insure the proper engagement of the pawls with the ratchet teeth on the rack bar.

It will thus be seen from the foregoing description, that a jack has been provided 65 wherein the cylindrical member may be ad-

justed to various lengths and which will be held in such adjusted position against the possibility of accidental lowering of the same and furthermore is positive in its action. The simplicity of my device further 70 more enables the same to be readily and easily operated and does not require the necessity of having to provide auxiliary holding means in connection therewith. Its use is not necessarily limited to holding the main 75 drive shaft in a corn sheller and may also be used for any other suitable purposes and I do not wish to limit myself to the particular manner in which my device is to be used.

From the foregoing description of the construction of my improved apparatus, it will be seen that I have provided a simple, inexpensive and efficient means for carrying out the objects of the invention, and while I have particularly described the elements best 80 adapted to perform the functions set forth, it is obvious that various changes in form, proportion and in the minor details of construction may be resorted to, without departing from the spirit or sacrificing any of the principles of the invention.

I claim:—

1. A jack of the class described comprising a tubular standard having a vertically extending slot at its upper end, an elongated cylindrical member slidably mounted in said tubular standard, a rack bar on the upper end of said cylindrical member and adapted to be in slidable engagement with said slot, a bracket extending from said standard, a transverse pin carried by the outer ends of said bracket, a pawl pivoted on said pin between the outer ends of said bracket, and adapted to engage said rack bar, means for normally holding said pawls in engagement with said rack bar, a lever fulcrumed on said pin, a lifting pawl pivotally mounted at its lower end on said lever, and adapted to have its free end in engagement with said rack bar above the first mentioned pawl, and a guide carried by said standard and extending outwardly therefrom for receiving said pawls.

2. A jack of the class described comprising a tubular standard provided with a vertically extending slot at its upper end, and a longitudinally extending slot at its intermediate portion, a cylindrical member slidably mounted therein, a rack bar on the upper end of said cylindrical member and adapted to be in sliding engagement with the first mentioned slot, a pin associated with the lower end of said cylindrical member and extending through said longitudinal slot for preventing the rotary movement of said cylindrical member in said tubular standard, a bracket extending from said standard, a transverse pin carried by the outer end of said bracket, a pawl pivoted on said pin, and adapted to engage said rack bar, means for

normally holding said pawl in engagement with said rack bar, a lever fulcrumed on said pin, and a lifting pawl pivoted on said lever and adapted to engage said rack bar above
5 said first mentioned pawl, a guide carried by said standard for said pawl, and means associated with said tubular standard and the

lower end of said cylindrical member, returning said cylindrical member to its normal position when said pawls are released from 10 engagement with said rack bar.

In testimony whereof I affix my signature.

JOHN CENDER.
